FIREPLACE SMOKE CHAMBER CONSTRUCTION

Application filed December 31, 1928. Serial No. 329,373.

The proper construction of a fireplace is one requiring considerable skill and as fireplaces are ordinarily constructed it is often difficult to properly proportion and construct the necessary passageways so as to secure the best results. The principal difficulty in such construction is the formation of the smoke chamber or part that connects the fire box with the flue. Usually the fireplace has to be completed after the walls and other parts of the building are finished so that it is difficult for the mason to have access to the passageway or to readily fashion the surrounding walls to leave a suitably shaped smoke chamber.

The objects of this invention are to provide means for forming a substantially perfect connection between the fire box and the flue or chimney; to provide a form or frame work which will indicate or insure the proper shape for the smoke chamber; to provide a metallic frame work to be used in building a fireplace connection; to provide a fireplace having a smoke chamber which is properly constructed and arranged to provide proper draft for the fireplace and also to provide means whereby any down draft in the chimney will be controlled or prevented from causing smoking; to provide a chimney smoke chamber or connection between the fire box and the flue having sufficient space at the back of the opening from the fire box to permit any down draft to be returned up the flue; and to provide such other desirable features and improvements in construction as will be described hereinafter.

In the accompanying drawings illustrating this invention.

Figure 1 is a front view of a fireplace showing our improved construction;

Figure 2 is a sectional view taken on the line 2—2 of Figure 1;

Figure 3 is a front view of our improved frame or form used in making the smoke chamber;

Figure 4 is a back view of the same; and Figure 5 is an end view of the same.

The fireplace shown in these drawings comprises a fire box 6 having a back wall 7 and end walls 8 and has an outlet or opening 9

leading into the smoke chamber 10. This opening which is usually long and narrow is preferably controlled by means of a damper 11 which may be of any ordinary or preferred construction; and is shown as being hinged 55 at 12 along the back of the opening.

The smoke chamber forms the connection between the fire box 6 and the flue or chimney 13 and is the part to which this invention particularly relates. In order to properly form 60 this chamber, we provide a frame 14, as shown particularly in Figures 3, 4 and 5. This frame conforms in general to the proper shape for the smoke chamber and is preferably formed of angle iron or the like. It 65 comprises ends 15, each of which has horizontal top angles 16 and bottom angles 17. The angles or bars 16 and 17 are connected by posts or connecting members 18 each of these being formed of two angle irons and preferably arranged so that bricks will fit between the angle irons and be supported thereby. The top angles 16 are fastened together at the back by a bolt 19 and the lower angles by a back cross piece or angle 20. The lower 70 angles 17 are preferably provided with outwardly projecting straps or supports 21 to assist in supporting the frame on the brick-work. The front 22 comprises end bars or angles 23 which are pivoted at 24 to the top 75 bars or angles 16 and are connected by bolts 25 to the bottom angles 17. The bolts 25 extend through slots 26 in the angles 23 and slots 27 in the angles 17 in order to permit the adjustment of the angle of the front frame 80 member. The angles 23 are connected at the top by angles 28 and at the bottom by angles 29. The angles 28 and 29 are further connected by bars or uprights 30. Each of these is preferably formed of a pair of angles and 85 they are spaced so that they provide supports for bricks which may be laid between these uprights. Legs or angles 31 are secured to the lower back angle 20 and extend downwardly, their lower ends being connected by 90 a longitudinal bar or angle 32.

As shown in the drawings, the back part of the frame is substantially vertical while the ends and front are arranged at the angles of approximately sixty degrees, which has 95 100

been found a desirable pitch for the corresponding walls of the smoke chamber. The front of the frame may be adjusted to permit variation in the depth or distance from the front to the back of the smoke chamber and also for variation in the width of the opening from the fire box.

In the construction of a fireplace with our improved frame or form, the brickwork is preferably carried up to approximately the top of the back arch and to the bottom of the smoke chamber, for instance, as indicated in Figure 2. The frame is then placed in position with the bar or angle 32 resting on the bottom of the smoke chamber and the straps or supports 21 may be supported on the brick-work at the ends of the fireplace. The end and front bricks may then be placed in position on the ends and front of the frame and the adjacent brickwork then carried up in the usual manner until connection is made at the top of the smoke chamber with the flue lining 33 which completes the connection between the fireplace and the flue. By means of this arrangement it will be seen that the smoke chamber will be properly proportioned and the walls thereof may be made smooth by any brick layer or mason, even if he has no particularly skill in the construction of fire-places. Furthermore, on account of the downwardly projecting legs 31 and cross bar 32, a space must be provided at the rear of the smoke chamber which extends downwardly to the bottom of this support which will preferably be below the pivot 12 of the damper 11.

With this construction, it will be seen that we not only provide a suitable connection for the up draft from the fireplace to the flue, but we also provide a space at the back of the smoke chamber so that if there is any down draft at the back of the flue or chimney, which is often apt to occur, the air will follow the directions indicated by the arrows so that when it strikes the shelf or bottom of the smoke chamber it will tend to be deflected upwardly at the back of the damper to join with the upwardly moving gases from the fireplace. This effectively prevents any down draft from causing smoking of the fireplace or blowing of the gases out into the room. While the damper may assist in directing such air upwardly, our construction would effectively prevent smoking of the fireplace, even if no damper is used.

Our improvement may be varied in the details of construction in order to adapt the same for different fireplaces or different conditions, and changes may be made within the spirit of this invention without departing from the scope thereof as set forth in the following claims, in which we claim:

1. A frame for constructing a fireplace smoke chamber, comprising ends formed of angle iron and converging toward the top, means for rigidly securing the ends together,

an adjustable front formed of angle iron and sloping from the bottom toward the top, said ends and front being adapted to receive bricks, and a downwardly extending frame member adjacent to the back which is adapted to rest on the smoke shelf. 70

2. A frame of the character set forth, comprising end members, means for securing the end members together, a front pivoted to the upper ends of the end members, means for adjustably connecting the front to the bottom of the end members, brackets extending outwardly from the end members, and a supporting bracket extending downwardly at the back of the frame. 75

3. In a fireplace construction, the combination of a fire box having an outlet at the top, a smoke chamber into which the outlet opens, said smoke chamber extending backwardly from the outlet and downwardly at the back 80 to approximately the level of the rear portion of the outlet, a metallic frame mounted in said smoke chamber and outlining the shape thereof, said frame being adapted to receive and support bricks on the front and ends thereof, and a flue connecting with the upper end of the smoke chamber. 85

4. A frame for a smoke chamber, comprising reticulated end members which are spaced apart at the top and diverge downwardly, a fastening member for fastening the end members together at the back thereof adjacent to the top, and a reticulated front which is pivotally connected at the top to the end members whereby the front may be adjusted with 100 respect to the end members. 105
